Patented Sept. 20, 1921.

2 SHEETS—SHEET 2.

UNITED STATES PATENT OFFICE.

JOHN LYNCH AND CHARLES McGUIRE, OF SEATTLE, WASHINGTON.

STUMP-CHOPPING MACHINE.

1,391,131.

Specification of Letters Patent. Patented Sept. 20, 1921.

Application filed March 7, 1921. Serial No. 450,224.

To all whom it may concern:

Be it known that we, JOHN LYNCH, CHARLES McGUIRE, citizens of the United States, and residents of the city of Seattle, county of King, State of Washington, have invented certain new and useful Improvements in Stump-Chopping Machines, of which the following is a specification.

Our invention relates to stump chopping machines, and more particularly to a machine of that character adapted to split and chop up stumps to such extent that they may readily and easily be removed from the ground.

The principal object of the present invention is to provide a portable, stump-chopping machine which operates after the fashion of a pile driver, and wherein the chopping, or cutting, blade is fixed at the lower end of a heavy reciprocally mounted shaft that may be mechanically raised and then dropped, so that the cutter will cut, or split, the stump against which it is directed.

Another object of the invention is to provide a device of the above described character, comprising means whereby the cutter carrying shaft may be moved rotatably within its support while in action, so as to adjust or regulate the direction of the blade to accomplish the best results, and other means whereby the chopping shaft may be inclined to different positions to best reach the object against which it may be directed.

It is also an object of the invention to provide a machine of the above character that may be used for other work outside of destroying stumps, such as for hole drilling purposes, post driving, chopping, etc.

In accomplishing these and other objects of the invention, we have provided the improved details of construction, the preferred forms of which are illustrated in the accompanying drawings, wherein—

Figure 1 is a side elevation of a stump chopping machine embodying the present invention.

Fig. 2 is a plan view of the same.

Fig. 3 is a front elevation of the machine.

Fig. 4 is an enlarged sectional, detail view of the chopping shaft guide sleeve, with the means for rotating the same, and for swinging it pivotally in a vertical plane.

Fig. 5 is an enlarged plan view of the shaft guide and its rotating means.

Fig. 6 is an enlarged side view of the shaft adjusting mechanism.

Fig. 7 is a detail view of the locking mechanism.

Referring more in detail to the several views of the drawings, wherein like reference numerals designate the same or like parts—

1 and 2 designate parallel runners, connected at their rearward ends by a cross beam 3 and at their forward ends by a cross beam 5, forming a portable base upon which is erected a derrick structure, comprising a pair of substantially upright beams 6 and 7, which are erected at the front end of the base with their upper ends drawn together and leaned forwardly thereof, as shown best in Figs. 1 and 2, and which are supported in this manner by brace or tie beams 8 and 9 which are fixed, at their lower ends, to the rearward end of the base at opposite sides thereof, and, at their upper ends are fixed by bolts or otherwise respectively to the upper ends of the beams 6 and 7. Vertical posts 10 and 11 are mounted, in spaced apart relation, upon the cross beam 5 and at their upper ends are fixed to the beams 8 and 9; these latter posts serving as a means of support for the chopping shaft control mechanism presently described.

Adjacent the rear of the base frame are also cross beams 12 and 13, upon which an engine as indicated at 14, is supported and whereby a drum 15, on which a hoisting cable 16 is wound, may be actuated.

Fixed upon the beams 8 and 9 adjacent their upper, forward ends, are bearings 17 and 18 wherein are pivotally contained the supporting trunnions 19 and 20 extending horizontally from opposite sides of a ring member 21. A sleeve 22 is rotatably contained within the ring 21 and is supported therein by means of a ring gear 23 that fits within the ring 21 and which is secured to the sleeve by means of rivets or bolts as indicated at 25. A flanged ring 26 is secured to the sleeve beneath the ring 21 which prevents longitudinal movement of the sleeve but does not prevent rotation thereof.

Mounted for reciprocation within the sleeve 22 is the chopper shaft 27. This may

be of considerable length and weight, and is equipped at its lower end with a cutter blade 28 for engaging and chopping a stump against which it may be directed by reciprocation of the shaft within the guide sleeve. A bracket 29 is fixed to the lower end of the shaft, and to this is attached the end of the cable 16 which, from the drum, extends over a sheave wheel 30 secured on a cross beam 31 on the beams 8 and 9 adjacent the bearings 17 and 18, and then extends downwardly to the bracket 29 so that the pull is substantially in the direction of the shaft no matter to what position it is directed. The driving mechanism of the drum would be such that the shaft could be raised and then dropped so that its weight would serve to drive the cutter blade into the object against which it was directed. Within the upper and lower ends of the sleeve 22, we have secured collars 34 and 35 and within these have provided guide grooves 36 wherein guide bars 37 that are secured longitudinally of the shaft, are adapted to slide to prevent it rotating within the sleeve.

To change the direction of the cutter blade, we have provided for rotating the sleeve, which incidentally causes like movement of the shaft and blade. This is accomplished by means of a gear wheel 40, that is fixed on the inner end of a short shaft 41 contained co-axially within the trunnion 20 of the ring 21, and meshes with the ring gear 23. A sprocket wheel 43 is fixed on the outer end of the shaft 41 and over this is extended a sprocket chain belt 44 which also operates over a sprocket wheel 45 on a shaft 46 rotatably mounted in the lower end 40 of the post 11. The latter shaft may be revolved by means of a crank 47 to cause rotation of the gear 40 and a consequent rotation of the sleeve 22 within the supported ring 21. A wheel 48 provided with peripheral notches 49 is also fixed on the shaft 46 and a dog 50 is fixed on the post 11 to be dropped into these notches to lock the same at any adjusted position.

To swing the shaft to different positions in the vertical plane, we have provided the following mechanism:

Supported revolvably in bearings 55 secured on cross bars 56 and 57 extended between the posts 10 and 11 and beams 6 and 7 respectively are threaded shafts 58 and 59. These are parallel and are disposed at opposite sides and adjacent the lower end of the sleeve 22, and at their rearward ends are equipped with sprocket wheels 60 and 61, which lie in the same plane of other sprocket wheels 62 and 63 mounted on cross bars 64 and 65 extended between the posts 10 and 11 respectively adjacent to the cross bar 56 and the lower ends of the posts 10 and 11. A sprocket chain 66 extends about

these wheels so that rotation of the wheel 63 by means of a crank 67 thereon will cause rotation of the shafts 58 and 59 in a like direction.

Threaded on the shafts 58 and 59 at opposite sides of the chopping shaft sleeve 22, are blocks 69 and 70 into which are pivotally extended the trunnions 71 and 72 of a ring 73 that is slidably mounted about the sleeve 22. 75

This construction provides that rotation of the shafts 58 and 59 will cause similar shifting of the blocks 69 and 70 therealong and this will cause the lower end of the sleeve to be swung inwardly or outwardly 80 to adjust the direction of operation of the chopping shaft accordingly.

In operation, the base is moved up to a stump as shown in Fig. 1, the chopping shaft is then raised and is inclined, by operation of the crank 67, to such position that it will be directed against the stump. The engine is then started to cause the raising and dropping of the pile driver, and, the operator by manipulating the cranks 47 and 67 can adjust the chopper to different positions desired. 85

Having thus described our invention, what we claim as new therein and desire to secure by Letters-Patent, is:

1. A machine of the character described, comprising a frame, a chopping shaft guide pivotally supported by said frame, a chopping shaft slidably mounted for reciprocation in said guide, means for adjusting the guide to change the direction of the chopping shaft, means for rotating the shaft within the guide and means for operating the shaft. 95

2. A machine of the character described, comprising a frame structure, a chopping shaft guide sleeve supported pivotally by said frame to swing in a vertical plane, a chopping shaft mounted for reciprocation in said sleeve and slidably keyed thereto and having a chopping blade at its lower end, means for effecting rotation of the sleeve, means for effecting adjustment of the sleeve about its supporting means to control the direction of operation of the chopping shaft and means for operating the shaft. 105

3. A machine of the class described comprising a base having a frame structure erected thereon to extend forwardly of the base, a ring member supported pivotally at 120 the upper end of said structure, a chopping shaft guide sleeve supported from its upper end for rotation within said ring, a chopping shaft slidably keyed within said sleeve, a chopping blade fixed at the lower end 125 of said shaft, mechanism operable to effect rotative movement of the sleeve within the supporting ring to adjust the direction of the blade, and means for swinging the sleeve to change the direction of operation of the 130

chopping shaft, means for locking the latter at adjusted positions, and means carried by the base frame for raising and dropping the chopping shaft.

5. 4. In a machine of the character described, a base, a frame structure erected upon the base to extend forwardly thereof, a ring member supported by trunnions at its opposite sides, at the upper end of the frame 10 to swing about a horizontal axis transversely of the base, a guide sleeve suspended rotatably from its upper end within said ring, a ring gear fixed about the sleeve, a shaft extended through a trunnion of said ring 15 having a gear fixed on the inner end thereof in mesh with said ring gear, and a sprocket wheel at the outer end of said shaft, a chopper shaft slidably keyed within said sleeve, a cutter blade at the inner end of the chopper 20 shaft, means for raising and dropping the chopper shaft, means for swinging the sleeve to effect an adjustment in the direction of operation of the shaft, a crank shaft fixed in the frame, a sprocket wheel on said 25 latter shaft, a chain belt extended about the former and last mentioned sprocket wheels whereby rotation of the crank shaft will cause rotation of the sleeve for the purpose set forth.

5. In a machine of the character described, 30 a base, a frame structure erected upon the base to extend forwardly thereof, a ring member supported by trunnions at its opposite sides, at the upper end of the frame to swing about a horizontal axis transversely 35 of the base, a guide sleeve suspended rotatably from its upper end within said ring, a chopper shaft slidably keyed within said sleeve, a cutter blade at the inner end of the chopper shaft, means for raising and 40 dropping the chopper shaft, a collar slidable on the lower end of said sleeve having laterally extending trunnions thereon, threaded shafts extended along opposite sides of said sleeve, blocks mounted on said shafts 45 and having said trunnions mounted therein, sprocket wheels on said shafts, a crank shaft fixed in the lower part of the frame, a sprocket wheel on said shaft and a chain belt extended over said sprocket wheels 50 whereby rotation of the crank shaft effects adjustment of the sleeve for the purpose set forth.

Signed at Seattle, Washington, this 1st day of March, 1921.

JOHN LYNCH.
CHARLES McGUIRE.
